UNITED STATES PATENT OFFICE.

RUTHERFURD SCOTT HARTZ, OF VANCOUVER, WASHINGTON.

AUTOMATIC SELF-STABILIZING PLANE FOR AEROPLANES.

1,149,827.

Specification of Letters Patent. Patented Aug. 10, 1915.

Application filed February 27, 1915. Serial No. 10,954.

To all whom it may concern:

Be it known that I, RUTHERFURD S. HARTZ, a citizen of the United States, and a resident of Vancouver, in the county of Clarke and State of Washington, have made certain new and useful Improvements in Automatic Self-Stabilizing Planes for Aeroplanes, of which the following is a specification.

- 10 My invention relates to improvements in flying machines of the type known as aeroplanes and has for its object to provide an automatic self stabilizing plane or planes to be used in aeroplane construction.
- 15 Another object is to dispense with numerous pieces of mechanism heretofore necessary in the stabilizing of aeroplanes and rendering the aeroplane self balancing and self righting.
- 20 With these and other objects in view my invention consists in a plane having an inherently stable body portion and an inclosing inherently flexible portion; it consists further in certain novel features of construction, arrangement and combination of parts as will be hereinafter more fully described and pointed out in the claims, reference being had to the accompanying drawings, in which,
- 25 Figure 1 is a front elevation of a flying machine showing my improvements applied thereto. Fig. 2 is a side elevation of the same. Fig. 3 is a top plan view of the plane or supporting member. Fig. 4 is a section on the line 4—4 of Fig. 3. Fig. 5 is a section on the line 5—5 of Fig. 3. Figs. 6, 7, 8 and 9 are diagrammatic views showing various positions assumed by the plane in falling and righting itself. Fig. 10 is a 30 fragmentary plan view showing a modified construction of flange. Fig. 11 is a section of the same on line 11—11 of Fig. 10. Fig. 12 is a fragmentary plan view showing a modification.
- 35 As shown in the drawings the plane consists essentially of two portions, a rigid central or body portion and flexible inclosing portion, the rigid portion having the general contour shown in Fig. 3; this portion
- 40 A which comprises the supporting means has the general outline of the body of a bird and its wings, B representing its perimeter or boundary the wings being represented by A' and as shown in Fig. 3; the breast portion is slightly curved rearwardly and each wing portion has its front edge curving

gradually to the rear until it reaches the tips which are rounded, thence the rear edges of the wings are composed of slightly convex curves to a point at each side of the rear center of the body portion where they merge by concave curves with a slight convex curve forming the rear edge of the body portion. The space inclosed within the dotted curved lines A² in this figure, represent the approximate position of the car with respect to the plane for carrying the propelling means, passengers, etc., and the point A³ is the approximate center of gravity of the plane and car; the front part of boundary B of the rigid portion has the form shown and meets the rear boundary line B at the rear ends of the wings A' the front and rear edge of the body portion A being higher than the point A³, the said body portion curving gently upwardly in all directions to the perimeter or boundary lines B, B from the point A³ or the center of gravity, as indicated in Figs. 4 and 5.

Merging with the main or rigid (non-flexible) portion A is the flexible flange C the boundary or edge of which is represented by the letter C' which partakes of the general shape of the boundary of the main portion. The flange C has a slightly rearward curved portion at the front center and then curves outwardly and rearwardly around the ends or tips of the wings, the flange gradually widening from points adjacent the front center to the wing tips and then extends around the rear boundary of the main or body portion its rear edge being approximately parallel with the rear boundary line of the inflexible portion, but the flange at the rear of the body and wings being wider than the flange at the front of the same; the flange at its junction with the body portion coincides with and takes up the curvature which begins at the center of gravity A³ and extends in all directions, but the curvature upward and outward becomes more abrupt through the width of the flange which is flexible and unstable, the flange becoming more and more flexible toward its extreme outer edge where it is exceedingly so, becoming very thin as shown in Figs. 4 and 5.

The dotted lines D in Fig. 3 indicate tapering springs or bows that permit the flexible outer edge of the flange to become more so as the outer edge is approached, but other means may be used to accomplish the same

purpose, and at these or other points the flange may be split and separated into sections similar to the feathers of a bird's wings.

5 As shown in Figs. 3 and 4 the portions within the perimeter or lines B, B are rigid or non-flexible, while the portion between the lines B, B and perimeter C' are flexibly increased in flexibility toward the outer 10 boundary or edge.

As shown in Figs. 3 and 4 the outer edge of the flexible flange is higher than the corresponding point of the stable or inflectionless portion, thereby forming a sort of basin.

15 The flexible flange portion may entirely surround or inclose the rigid portion or it may extend around only a portion of the perimeter B of the rigid portion leaving a space at the front as indicated in Fig. 12.

20 Or, as illustrated in Figs. 10 and 11 the flange may be built of sections similar to the construction and location of the feathers in the wing of a bird, and the same effect will be produced as that produced by a one piece 25 flange.

It will also be noticed that the tips of the wings and a considerable portion of the central or body member and also of the wings are to the rear of the line of the center of gravity as represented at A³. The plane may be made of a single piece of suitable material or it may be made up of separate parts of suitable material and construction, but the construction and arrangement 35 must be such as to preserve the essential features of the device, the rigid main body or sustaining portion and a self flexing flange surrounding all or a part of its perimeter or boundary:

40 In the diagrammatic views Figs. 6, 7, 8 and 9, is illustrated the various positions assumed by the plane in fall, righting, etc., thus: Fig. 6 represents the aeroplane designated by the letter P dropped with the front 45 of the plane downward; the air pressure represented by arrow striking the forward edge of plane P bends the flange backward or rather upward until it becomes practically non-flexible and then deflects about

50 the curved surface, in this case, to the right, thereby pushing the front edge to the left; at the same time the air pressure forces the upper or rear flange upward and backward and deflects to the left forcing the rear of 55 the plane to the right; there being a pressure at both edges, and, both pressures being opposite, the plane is caused to right itself. The rear of the aeroplane having the largest flange, sustains the greatest pressure, and in

60 Figs. 6 and 9 the plane follows the forward point thereof, while in Fig. 8 the plane glides to the rear on the curve of the rear flange, as indicated by the dotted lines and arrows, then when righted, glides directly 65 forward; in Fig. 7 the plane glides upon the

lower wing tip it having the greater curve and pressure upward until righted, when it changes direction and glides toward its forward edge; in all of these examples the plane turns from the greatest pressure 70 point; the flange also, when the plane is righted acts as a propelling force as it is so proportioned as to balance the plane, while at the same time causing pressure to be exerted from the rear; in other words, the 75 flange or flexible edge is so proportioned as to overbalance the parts that should be overcome, when the equilibrium is overcome and when the balance is regained to continue and preserve the balance, at the same time pressing the entire machine forward.

The entire flange is a rudder, or should it be constructed, as not in one piece, but in many, as shown in Figs. 10 and 11, it would then become a number of rudders working 80 jointly, each exerting the necessary power to gain the required end. When the air pressure comes from the top, it flattens out the flange to a great extent and so enables the machine to continue its flight or movement 85 with very slight resistance. For elevating and depressing purposes, as also for lateral, auxiliary rudders will be used.

Should the motor fail this aeroplane becomes more or less of a glider owing to its 90 construction and instead of dropping suddenly to the earth, will glide down.

With this improved plane no matter in what position the wings are held, whether inverted, on edge or on end, they will right 100 themselves restoring equilibrium without the assistance of manual or mechanical means.

My improved plane may be used with monoplanes, biplanes, or flying machines 105 having any number of planes.

I claim:

1. In an aeroplane, a sustaining plane comprising a rigid inflectionless member elongated transversely from a central body 110 portion to constitute wings, and a flexible flange extending across the rear of the said body portion and wings around the ends of the wings and portion of its front edge.

2. In an aeroplane, a sustaining plane comprising a rigid body portion having the general contour of a bird with out stretched wings, and a flexible flange projecting from the perimeter thereof and inclosing the same.

3. In an aeroplane, a sustaining plane comprising a rigid main or body portion and laterally extending wing portions, and a flexible flange surrounding the perimeter thereof, said flange increasing in width 125 from the front center to the tips of said wing portions.

4. In an aeroplane, a sustaining plane comprising an inflectionless laterally elongated body member and a surrounding flex- 130

ible flange member, the upper and lower surfaces of said body and flange members curving upwardly in all directions from a common center.

5. In an aeroplane, a sustaining plane comprising a rigid inflectionless member elongated transversely from a central portion to constitute wings, the front edge of said member curving rearwardly, and the 10 rear edge thereof curving inwardly to the central portion and a self flexing flange surrounding said rigid member, the upper and lower surfaces of the rigid member and the flange member curving upwardly from the 15 center of gravity of the body portion, as a common center.

6. In an aeroplane, a sustaining plane comprising a rigid inflectionless body portion, and a flexible flange surrounding the same 20 said flange tapering to its outer edge whereby the flexibility of said flange is increased toward its outer edge.

7. In an aeroplane, a sustaining plane comprising a rigid inflectionless body portion, and an upwardly curved inherently 25 flexible flange surrounding the perimeter thereof, the inner edge of said flange coinciding with the outer edge of the rigid portion and tapering in thickness outwardly to 30 its edge.

8. In an aeroplane, a sustaining plane

comprising inflectionless body and wing members, said wings projecting laterally and rearwardly from the body member to the rear of the center of gravity of the 35 plane and a flexible flange projecting from the perimeter of the plane.

9. In an aeroplane, a sustaining plane, consisting of an inflectionless main or body portion and a surrounding flexible flange 40 member the body and flange member curving upwardly and outwardly in all directions from the center of gravity of the plane, the curvature of the flange member increasing with increasing distance from 45 the center of gravity.

10. In an aeroplane, a sustaining plane consisting of an inflectionless main or body portion, and a flexible border inclosing the same and consisting entirely of a series of 50 independent flexible flange sections.

11. In an aeroplane a sustaining plane consisting of an inflectionless member elongated transversely from a central body portion to constitute wings, and a flexible border inclosing said member and consisting entirely of separate independently flexible 55 flange sections.

RUTHERFURD SCOTT HARTZ.
